UNITED STATES PATENT OFFICE

2,550,294

BEDSPRING

John Platis, Corpus Christi, Tex.

Application June 18, 1947, Serial No. 755,353

7 Claims. (Cl. 5—246)

1

This invention relates to novel and useful improvements in bed springs and a particular purpose of the present invention is to provide bed spring means useful particularly in conjunction with my improved mattress illustrated co-pending application #743,494 filed April 24, 1947.

An object of this invention is to provide joinder, web means adapted to be positioned between selected springs which are conventional in mattresses.

Another object of this invention is to provide an improved mattress characterized by an insert, resilient in nature, secured between selected springs of a mattress.

A further purpose of the present invention is to provide means for retaining said insert in a selected, desired position relative to the remainder of a mattress.

Another purpose of this invention is to provide an extremely simple, uncomplicated device of the nature described which is relatively inexpensive and commercially feasible.

Ancillary objects and features of novelty will become apparent as the description of the preferred embodiment of the present invention proceeds, which embodiments are exemplified in the accompanying drawings, wherein:

Figure 1 is a perspective view of the preferred form of the present invention;

Figure 2 is an elevational front view of the preferred form of the present invention;

Figure 3 is a plan view of the insert utilized in the present invention; and

Figure 4 is a perspective view of a modified form of the inventive principles.

Referring now in detail to the illustrated preferred embodiments of the present invention, like reference characters are used throughout to indicate similar elements.

As set forth in my co-pending application, described above, this invention is to be utilized in conjunction with an improved mattress particularly advantageously used in hospital treatment, athletes' conditioning rooms and the like. The sectional mattresses described in the aforementioned pending application have inserts interposed between the said sections and these inserts are positionable above the insert forming the nucleus of this inventive principle.

As seen in Figures 1 and 2, a plurality of springs 10, conventional in nature, are provided in the usual series and joinder members 12 are used in retaining the said springs 10 in the desired, operative position relative to each other.

Taking now the first modification of the present

invention, reference is made particularly to Figures 1 and 3. There is disclosed a plurality of substantially parallel rods 14 having resilient curvilinear connecting means therebetween. The said resilient curvilinear connecting means are shown as substantially U-shaped wave type springs 16 rigidly secured to the said rods 14. The springs 16 being attached at their ends, form a cradle below the general upper surface of the device to accommodate a connecting member 24 for mattress sections 22. Any suitable, conventional securing means may be utilized in retaining the rods and curvilinear, resilient members 16 in the desired relative position. Of course, small rivets, welding, brazing or a variety of other equivalent means may be utilized if so desired. The said rods 14 are positioned on the joinder members of springs and are retained in fixed, immovable relative position. Of course, if so desired, the said rods 14 may be also joined to the springs 10 as disclosed in Figure 1. As seen in Figure 2, the said insert or web is positioned between selected springs 10. Also, if found desirable, compression springs 18 may be secured to the upper portion of the said insert and selected lower joinder member 12. These springs are used for the purpose of retaining the invention in the desired relative position.

It is noted at this point that tie wires may be utilized in place of the said compression springs 18, the said wires extending between the lowermost portion of the insert and a selected upper joinder member 12.

Referring now to the second embodiment of the present invention, reference is made to Figure 4. Here it is noted that rods 14 are provided similar to the said rods in the first embodiment of the present invention. Also, curvilinear, resilient members 20 are secured to said rods 14, extending thereacross. The said curvilinear, resilient members 20 having the same properties as the spring member 16, the difference in construction resulting only in a different degree of resiliency. The function and purpose of the insert disclosed in Figure 4 is similar to that described hereinabove.

Referring now to Figure 2 there is disclosed a mattress 22 positioned on the spring assembly and the connecting member 24 is shown operatively joining a second section of the said mattress 22. It is in this environment that the invention described hereinabove is particularly suited, however, as is understood to those skilled in the art, other utility of this inventive concept is embraced within the purview of the pres-

ent invention, an example being the use of the present invention as the inner spring assembly for a mattress with all the usual, conventional padding, ticking and braces.

While there has been described and illustrated a preferred embodiment of the present invention, capable of performing all of the specifically mentioned objections as well as numerous ancillary objects, it is apparent that various changes including rearrangement of elements, changes as to size and shape may be made without departing from the spirit of the invention. Accordingly, limitation is sought only in accordance with the scope of the following claims.

Having described the invention, what is claimed as new is:

1. An insert for bed springs comprising a substantially U-shaped resilient web adapted to be interposed between selected bed springs, and said web depending substantially below the upper level of the bed springs to form a cradle to receive a mattress connecting means.

2. An insert for bed springs comprising a substantially U-shaped resilient web adapted to be interposed between selected bed springs, said web comprising a plurality of rods having resilient curvilinear members extending thereacross, and said web depending substantially below the upper level of the bed springs to form a cradle to receive a mattress connecting means.

3. An insert for bed springs comprising a substantially U-shaped resilient web adapted to be interposed between selected bed springs, said web comprising a plurality of resilient members and means for joining the terminal portions thereof, and said web depending substantially below the upper level of the bed springs to form a cradle to receive a mattress connecting means.

4. An insert for bed springs comprising a substantially U-shaped resilient web adapted to be interposed between selected bed springs, said web comprising a plurality of resilient members and means for joining the terminal portions thereof,

said joining means comprising a plurality of substantially parallel rods, and said web depending substantially below the upper level of the bed springs to form a cradle to receive a mattress connecting means.

5. Extension means for mattress supports comprising a series of bed springs having joinder members, a substantially U-shaped resilient web interposed between selected springs, and said web depending substantially below the upper level of the bed springs to form a cradle to receive a mattress connecting means.

6. Extension means for mattress supports comprising a series of bed springs having joinder members, a substantially U-shaped resilient web interposed between selected springs, said web including rods secured to said joinder members, resilient tie members operatively associated with said rods, and said web depending substantially below the upper level of the bed springs to form a cradle to receive a mattress connecting means.

7. Extension means for mattress supports comprising a series of bed springs having joinder members, a substantially U-shaped resilient web interposed between selected springs, said web comprising resilient curvilinear members and means for securing said curvilinear members to said joinder members, and said web depending substantially below the upper level of the bed springs to form a cradle to receive a mattress connecting means.

JOHN PLATIS.
